Primary Examiner — Rhea Shields*(74) Attorney, Agent, or Firm* — Foley & Lardner LLP(57) **CLAIM**

We claim the ornamental design for a hearing aid battery package, as shown and described.

DESCRIPTION

FIG. 1 is a front perspective view from above of the claimed battery package design;

FIG. 2 is a front view according to the claimed design;

FIG. 3 is a rear view according to the claimed design;

FIG. 4 is a right side view according to the claimed design;

FIG. 5 is a left side view according to the claimed design;

FIG. 6 is a top view according to the claimed design; and,

FIG. 7 is a bottom view according to the claimed design.

In the drawings the broken lines illustrate portions of the hearing aid battery package that form no part of the claimed design. Oblique lines show a transparent surface.
